US00D683079S

(12) **United States Design Patent**
Schmidt et al.

(10) **Patent No.:** **US D683,079 S**
(45) **Date of Patent:** **** May 21, 2013**

(54) **HELMET LINER**

(75) Inventors: **Joshua Schmidt**, Lakewood, OH (US);
Ron Szalkowski, Lakewood, OH (US);
Morgan McLennan, Parma Heights,
OH (US)

(73) Assignee: **Intellectual Property Holdings, LLC**,
Cleveland, OH (US)

(**) Term: **14 Years**

(21) Appl. No.: **29/403,709**

(22) Filed: **Oct. 10, 2011**

(51) **LOC (9) Cl.** **02-03**

(52) **U.S. Cl.**

USPC **D29/122**

(57) **CLAIM**

The ornamental design for a helmet liner, as shown and described.

DESCRIPTION

FIG. 1 is a bottom perspective view of a helmet liner showing our new design;

FIG. 2 is a bottom plan view thereof;

FIG. 3 is a side elevation view thereof, wherein the left side, right side, front and rear views are identical; and,

FIG. 4 is a top plan view thereof.

The broken lines shown in the drawings are for illustrative purposes only and form no part of the claimed design.
